UNITED STATES PATENT OFFICE.

EDWARD J. HARVEY, OF RACINE, WISCONSIN.

DESIGN FOR AN AUTOMOBILE BUMPER.

Application filed March 24, 1924. Serial No. 9,052. Term of patent 14 years.

To all whom it may concern:

Be it known that I, EDWARD J. HARVEY, a citizen of the United States, residing at Racine, in the county of Racine and State of Wisconsin, have invented a new, original, and ornamental Design for Automobile Bumpers, of which the following is a description, reference being had to the accompanying drawing, forming part thereof.

The figure is a perspective view of the automobile bumper showing my new design.

I claim:

The ornamental design for an automobile bumper as shown.

EDWARD J. HARVEY.

In presence of—
J. A. JONES.
